CLAIM

The ornamental design for a combined mirror and shaving gear holder, substantially as shown and described.

DESCRIPTION

FIG. 1 is a perspective view of a combined mirror and shaving gear holder showing my new design;

FIG. 2 is a top plan view thereof;

FIG. 3 is a front elevational view thereof;

FIG. 4 is a side elevational view thereof;

FIG. 5 is a back elevational view thereof;

FIG. 6 is a bottom plan view thereof; and

FIG. 7 is a sectional view thereof taken along line 7—7 of FIG. 5.
